UNITED STATES PATENT OFFICE.

FREDERICK HOHLFELDER AND VARNUM FRASIER CARPENTER, OF CLEVELAND, OHIO; SAID CARPENTER ASSIGNOR TO SAID HOHLFELDER.

HORSE-POWER.

SPECIFICATION forming part of Letters Patent No. 369,449, dated September 6, 1887.

Application filed February 3, 1887. Serial No. 226,465. (No model.)

To all whom it may concern:

Be it known that we, FREDERICK HOHLFELDER and VARNUM FRASIER CARPENTER, citizens of the United States, residing at Cleveland, in the county of Cuyahoga and State of Ohio, have invented certain new and useful Improvements in Horse-Powers; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 The object of this improvement is a horse-power of simple, compact, and economical construction and efficient operation, in which the parts are connected and supported in their true relative position to each other by a frame. 20 These results are attained in the mechanism illustrated in the drawings herewith filed as part of this application, in which the same letters of reference denote the same parts in the different views.

25 In the drawings, Figure 1 represents an end elevation of a horse-power embodying the features of our improvement. Fig. 2 is a transverse longitudinal vertical section taken on the line α α , Fig. 1. Fig. 3 represents a plan 30 of a device used in connection with the machine.

35 A, A', A², A³, and A⁴ represent the frame to which the parts are connected and by which they are supported. The part A' is a rectangular shell extending from the base A, and is provided at its top with a vertically-perforated cylindrical extension, A¹, which is finished at its circumference, for the purposes hereinafter set forth.

40 A² is a vertical extension from the base A, and is provided with a vertical recess adapted to receive a shaft or gear-arbor, B, which is snugly fitted thereto, and which is firmly secured within the extension A² by set-screws, 45 as shown at a². The part A³ is connected at its top by means of an integral brace-extension, a', with the part A'.

50 A³ is a vertical extension of the part A, provided with a horizontal perforation made to receive and form a bearing for a shaft, G, which is provided with an additional bearing, G',

and thereby arranged to support a driving-pulley, F.

The base A is centrally provided with a recessed vertical extension, a¹, which forms a 55 socket for the reception of a shaft or gear-arbor, H, which is rigidly secured thereto by one or more set-screws, as shown at h. The shaft H is set into the socket in the extension a¹ through the corresponding perforation or 60 bearing in the metal frame-extension A⁴.

E is a bevel-gear on the shaft H, on which it is arranged to turn.

D' is a pinion-wheel on the shaft H, on which it is also arranged to turn. The pinion D' is 65 connected with the bevel-gear E by means of a clutch, (indicated at d,) by reason of which force applied to the pinion D' will cause the bevel-gear to turn therewith.

D is a gear-wheel on the shaft B, rigidly secured to the vertical frame-extension A², as 70 described. The gear-wheel D is arranged to turn on the shaft B.

C is a pinion on the shaft B, also arranged to turn thereon. The pinion C is connected 75 with the gear-wheel D by means of a clutch, (shown at d²), by reason of which motion imparted to the pinion C will give corresponding motion to the gear-wheel D.

C is a gear-wheel having a hub suitably 80 fitted to the vertical frame-extension A⁴, on which the gear-wheel C is arranged.

K is a two-armed lever or sweep secured to the gear-wheel C by means of two or more bolts, c e, inserted through perforations in the 85 body of the wheel C, and through the lever K, and through a ribbed cast-metal cap, K', at the top of the lever K. A second lever, K², is placed in the opening or space in the ribbed cap K' at right angles to the lever K.

90 E' is a bevel-gear on the shaft G, and arranged to mesh with the bevel-gear E on the shaft H.

G² is a device for protecting the belt-connection of the horse-power with the machine 95 to be driven. It is composed of a metal frame made substantially in the form shown and provided near its ends with friction-rollers g, g', g², and g³, intermediate of which the upper part of the frame G² is provided with openings, 100 in order that the upper part of the belt may pass between the rollers and the lower part of

the belt to pass under the rollers $g' g^3$, as shown in Fig. 1. The rollers $g' g^3$ are journaled upon a higher plane on the part G^2 than the rollers $g' g^3$, so as to prevent contact of the belt, as 5 clearly shown in the same figure.

Operation: In the operation of the machine the gear-wheel C, which is put in motion by the lever K, gives motion to the pinion C', which, by reason of the clutch described, gives 10 corresponding motion to the gear-wheel D, which imparts corresponding motion to the pinion D', which latter, by reason of its clutch, connects with the bevel-gear E, and motion is thereby imparted to the driving-pulley F 15 on the shaft G through the bevel-gear E', which meshes with the bevel-gear E on the shaft H. The vertical extension A^3 of the frame A is finished at its upper end to conform to the correspondingly-finished size of the shaft G. The 20 gear-wheel h' is secured to shaft G by means of set-screws. The lower end of the hub-wheel E and the upper end of the vertical extension a^3 are finished bearings. The upper end of the vertical frame-extension A^2 is finished, and 25 forms a bearing for a correspondingly-finished lower end of the hub of the gear-wheel D. The lower end of the hub of the wheel C is finished, and the extension A' of the frame is finished at the base of the extension A^4 , and such 30 finished base forms a bearing for the gear-wheel C.

Having fully described the features of our invention, what we claim as new, and desire to secure by Letters Patent, is—

1. In a horse-power, the frame consisting of 35 a base, A, having integral therewith vertical socketed extension A^2 , provided with brace a' , central socketed extension, a^3 , and horizontally-perforated extension A^3 , and the hollow rectangular shell A' , secured to the base A, and 40 having a cylindrical perforated bearing, A^4 , projecting upwardly and forming a bearing for the gear-wheel C, substantially as and for the purposes set forth.

2. The combination, with a frame, the shafts 45 B H, journaled therein, the gears D C' on the shaft B, and the clutch d^2 between said gears, of the gears C, D', and E on the shaft H, the clutch d between the gears D' and E, the shaft G, arranged at right angles to the shafts H and 50 B, and the drive-pulley F on said shaft, meshing with the pinion E, all substantially as described.

In testimony whereof we affix our signatures in presence of two witnesses.

FREDERICK HOHLFELDER.
VARNUM FRASIER CARPENTER.

Witnesses:

B. LAMSON,
A. J. MICHAEL.
